UNITED STATES PATENT OFFICE.

WILLIAM M. DAVIDSON, OF ST. LOUIS, MISSOURI, ASSIGNOR TO WILLIAMS PATENT CRUSHER & PULVERIZER CO., OF ST. LOUIS, MISSOURI, A CORPORATION OF MISSOURI.

HOPPER DUST-ARRESTER.

1,322,546.

Specification of Letters Patent. Patented Nov. 25, 1919.

Application filed November 29, 1918. Serial No. 264,632.

To all whom it may concern:

Be it known that I, WILLIAM M. DAVIDSON, a citizen of the United States, residing at St. Louis, State of Missouri, have invented certain new and useful Improvements in Hopper Dust-Arresters, of which the following is a specification.

This invention relates to certain new and useful improvements in hopper dust arresters for reducing machines, the peculiarities of which will be hereinafter described and claimed.

The main object of my invention is to provide means whereby the hopper of a reducing machine used for pulverizing lime, coal and similar materials, may be prevented from discharging the dust of the ground material from said hopper while the coarse material is being fed thereinto.

20 In the accompanying drawing on which like reference letters indicate corresponding parts, Figure 1 represents a sectional elevation through a reducing machine exemplifying my invention; and Fig. 2 a partial 25 plan view of the same.

The letter A designates the shaft of a rotor consisting of hammers B and hammer supports, such as rods C and disks D, mounted on said shaft,—said rotor coöperating 30 with a suitable cage E located in the casing F of a reducing machine, that is provided with a hopper G and a cover H, preferably eccentric, as shown in Fig. 1.

In the operation of machines of this class, 35 trouble is experienced on account of the blowing out through the hopper, of the dust from the finely ground or pulverized material being reduced within the casing.

I have found by practical experiment that 40 this trouble is mainly or wholly eliminated by the provision of a rectangular box directly adjacent to the hopper and extending across the width of the hopper from side to side of the said cover. This box is preferably cast integrally with the cover but may be otherwise formed. It is preferably rectangular and consists of sides I substantially in the same plane of the sides of the cover H, a back J extending vertically up- 45 ward from the arched top of said cover, and making an acute angle with said cover, a front K provided with an inwardly turned lip L substantially parallel to the sloping bottom of the hopper G, and a top M. I

prefer to make the lip L adjustable vertically by means of a slot l and bolt N therein, adapted to allow of the adjustment of said lip up and down as indicated by dotted lines in Fig. 1. It will be observed that said lip is substantially in the horizontal 55 plane through the rotor shaft and tangent to the hammer circle and therefore a slight adjustment up and down will not vary, to any appreciable extent, the distance between the path of the hammers B and the inner 60 and lower end of said lip. From my experience, I have found it to be necessary that the inner end of said lip be directly adjacent to the path of the hammers in order to produce 65 the desired effect. Fig. 1 shows by arrows 70 below the lip in said hopper, the action of the air currents of dust when the lip is properly adjusted and the proper proportions are obtained in said box. That is to say, I have observed the dusty air current 75 turning over and over in circular motion and in a direction corresponding, at the bottom, to the inward flow of material. Just above the surface of the inwardly flowing material and between the material and the 80 circularly moving dust current below said lip, there is a clear space comparatively free from dust, as though the air from outside were being carried along and downwardly 85 with the inflowing material.

It is desirable that the dust be discharged through the cage with the ground material and when an exhaust fan handles the ground up material there is little or no discharge 90 of dust from the hopper of the machine. When an exhaust fan is not used my device is especially effective and desirable in preventing the discharge of these dust currents at the hopper and causing them to be delivered through the grinding cage instead of 95 out through the hopper.

I have found it essential to the desired working of this dust arrester, that the width W of the box between the walls K and J, be made of such dimensions that it will bear a 100 relation to the hammer circle radius of substantially one-half to two-thirds of said radius. For instance, when said radius (designated by the letter R in Fig. 1) is 15 inches, the width of said box would be about 105 8 inches. I have found that if such box were made 6 inches in width (which is less than one half of the radius mentioned), the

desired effect is not obtained. Apparently the 8 inches may be increased to perhaps 10 inches without materially affecting the proper action of said box, so that it may be said that the width of said box may range between one-half to two-thirds of the radius of the hammer circles.

Another point is the height of the said box above the arched cover where the wall 10 J joins the same. This height H. T. with a width of 8 inches and a radius of 15 inches, is in practice 14 inches, or substantially the same dimension as the said radius. I have applied this dust arrester to reducing machines such as coal crushers of the Williams type, and have even successfully pulverized burnt lime in such a machine, and eliminated all or practically all the dust that formerly, in other constructions, was blown out 20 of the hopper, but in my improved construction was prevented from so doing. It is evident that when pulverizing such material as burnt lime, the elimination of dust is of great practical advantage, and I have endeavored to the best of my ability to give 25 the proportions of the box above described, as representing the successful outcome of my experiments, although not being wholly able to explain the scientific reason for the 30 efficient working of the same. Such proportions however I have followed in my own practice in the manufacture of such machines, and submit the same that others

versed in the art may be able to produce similar results.

35

I claim:

1. A machine of the character described, comprising rotary hammers, a casing having a side hopper inlet and cover, and a rectangular box, open below, consisting of vertical side and end walls and a top, the lower end of the front side wall being substantially tangent to the hammer circle near the central horizontal plane, and the back side wall being connected at an angle with the 40 cover,—the horizontal width between said front and back walls being not less than one half the hammer radius, nor more than two thirds of said radius, and the vertical height 45 being substantially equal to said radius, substantially as described. 50

2. In a machine of the character described having a side inlet hopper, the herein described rectangular box located adjacent said inlet, and open below, and provided on its lower front edge with a vertically extendible inturned lip located directly adjacent to the path of the hammers near the central horizontal plane, and operable substantially tangent to the hammer circle, and 55 means to effect such adjustment up and down past the ends of the hammers, substantially as described. 60

In testimony whereof I have affixed my signature.

WILLIAM M. DAVIDSON.
